BELT SUPPORTED BATTERY CASE

Adam L. Kinskie, Morristown, Tenn.

Application April 25, 1950, Serial No. 158,000

2 Claims. (Cl. 150—52)

1

This invention relates to a belt receptacle, such as a belt supported battery case, and more particularly to a case for supporting the battery for a miner's head lamp.

It is among the objects of the invention to provide an improved battery case and support therefor so arranged that the case is loosely supported from a belt and is not bound against the body of the wearer in a manner to cause chafing of the skin or other discomfort, which protects the battery against perspiration and protects the wearer's clothes against battery acid, which is formed of flexible material and secured together by separable fasteners so that a battery can be easily placed therein or removed therefrom, and which is simple and durable in construction, economical to manufacture, and neat and attractive in appearance.

Other objects and advantages will become apparent from a consideration of the following description and the appended claims in conjunction with the accompanying drawing wherein:

Figure 1 is an elevational view of a fragmentary portion of a human figure showing the manner in which the battery case of the invention is worn;

Figure 2 is a top plan view of a battery case and carrying belt assembly illustrative of the invention;

Figure 3 is a cross sectional view on an enlarged scale on the line 3—3 of Figure 2;

Figure 4 is a cross sectional view on the line 4—4 of Figure 3;

Figure 5 is a perspective view of the battery case and a fragmentary portion of the carrying belt; and

Figure 6 is a perspective view similar to Figure 5 showing a somewhat modified arrangement for attaching the battery case to the belt.

With continued reference to the drawing, the assembly comprises, in general, a battery case 10 supported on a belt 11.

The belt 11 comprises an elongated strap 12 of heavy leather having parallel longitudinal edges and having at one end a loop 13 in which a front buckle 14 is secured. The buckle 14 has a width less than the strap portion of the belt and the end portion of the strap opposite the buckle 14 is reduced in width and provided with a series of spaced apart apertures to receive the buckle tongue. The reduction in the width of the buckle and of the buckle engaged portion of the belt prevents the buckle of the wide belt from chafing the skin of the wearer or causing other discomfort.

2

A strap retaining loop 15 is mounted on the belt adjacent the loop 13 to receive the portion of the belt extended through the buckle 14.

Two loops 16 and 17 are secured to the outer side of the belt at spaced apart locations between the ends of the belt, and a buckle 18 is secured to the belt by the loop 16 while a similar buckle 19 is secured to the belt by the loop 17. An attaching strap 20 provided with a series of spaced apart holes or apertures near each end thereof is received at one end in the buckle 18 and at its opposite end in the buckle 19 and extends along the outer side of the belt strap 12. The buckles 18 and 19 and the strap 20 have a width materially less than the width of the belt strap 12 and the loops 16 and 17 are located along the length of the belt strap so that, when the belt is worn, as illustrated in Figure 1, the strap 20 will be disposed over one hip of the wearer, the buckles 18 and 19 being spaced apart a distance somewhat greater than the width of the battery case 10.

The battery case 10 comprises a rectangular back plate 21 of heavy leather or other suitable flexible material, having an area somewhat greater than the area of a major surface of a battery to be supported in the battery case. This back plate 21 has a top edge 21^a and a bottom edge 21^b and two substantially parallel side edges 21^c and 21^d, respectively, and is provided with two spaced apart vertical slots 22 and 23 disposed at respectively opposite sides of the mid-width location of the back plate and at substantially equal distances from such mid-width location. The two slots 22 and 23 are disposed intermediate the length of the back plate 21 but nearer the top edge 21^a than the bottom edge 21^b of the back plate and the attaching strap 20 is threaded through these slots to connect the back plate 21 of the case to the belt strap 12.

In the arrangement shown in Figure 5, the portion of the strap 20 between the slots 22 and 23 is disposed at the back side of the back plate, that is, the side of the back plate nearest the belt strap 12 and the end portions of the strap 20 are disposed at the side of the back plate 21 remote from the belt strap 12. In the arrangement illustrated in Figure 6, this connection is reversed, the portion of the strap 20 between the slots 22 and 23 being disposed at the side of the back plate 21 remote from the belt strap 12 and the end portions of the strap 20 being disposed between the back plate 21 and the belt strap. In the arrangement shown in Figure 6, the slots 22 and 23 are also spaced apart a distance some-

what greater than the distance between these slots in the arrangement shown in Figure 5.

In the arrangement shown in Figure 6, the battery is supported entirely by the battery case while in the arrangement shown in Figure 5 the end portions of the strap 20 at opposite sides of the pair of slots 22 and 23 pass through loops on the battery and support the battery from the belt, the battery case in this arrangement merely providing a cover for the battery.

A flap 24 is secured along one edge to the back plate 21 along one side edge of the latter by the stitching 25 and this flap has a width such that it provides two side wall portions 26 and 27 and a front wall portion 28 extending between the side wall portions and having a width only slightly less than the width of the back plate 21. The side wall portions 26 and 27 have a width slightly greater than the thickness of the battery to be supported in the case and are joined to the front wall portion 28 along respectively opposite edges of the latter and extend at right angles thereto. The flap 24 reaches upwardly from the bottom edge 21^b of the back plate 21 and its upper edge 24^a is spaced below the top edge 21^a of the back plate 21 and is substantially on a level with the upper ends of the slots 22 and 23. The side wall portion 26 is cut down as indicated at 29 in its upper edge adjacent to the back plate 21 to receive the corresponding end portion of the strap 20, while the upper edge 26^a of the other side wall portion 26 is depressed below the level of the other end portion of the strap 20.

A flap 30 is secured along one edge to the back plate 21 along the side edge of the latter opposite that to which the flap 24 is secured at 25 and this flap 30 has a width slightly less than the width of the side wall portion 26 of the flap 24. The flap 30 is secured to the back plate 21 by the stitching 31 and extends at right angles from the back plate 21 along the inward side of the side wall portion 27 of the flap 24 when the case is closed, the side wall portion 27 being unsecured to the back plate 21. The flap 30 has a length substantially equal to the length of the flap 24 and extends substantially to the bottom edge 21^b of the back plate 21. The flap 30 is also provided in its upper end adjacent the back plate 21 with a notch 32 like the notch 29 which receives the corresponding end portion of the strap 20.

A receptacle in which the lower end of the battery is adapted to be seated is formed by a third flap 33 secured to the back plate 21 along the bottom edge 21^b of the back plate by the stitching 34 and comprises a bottom wall portion 35 which extends perpendicularly outward from the back plate along the bottom edge of the latter, a front wall portion 36 which extends perpendicularly upward from the edge of the bottom wall portion 35 remote from the back plate 21 and two side wall portions 37 and 38 which extend from the opposite ends of the front wall portion 36 along the opposite ends of the bottom wall portion 35 to the back plate 21 being substantially perpendicularly disposed to both the back wall portion 36 and the bottom wall portion 35.

The side wall portion 27 of flap 24 carries near its free edge two snap fastener elements 39 and 39' and the flap 30 carries two complementary snap fastener elements 40 and 41 of which the lower element 41 is also engaged with the end wall portion 38 of the bottom flap 35. The elements 38 and 39 are engageable respectively with the elements 40 and 41 to secure the flap 24 to the wall of the receptacle releasably holding said

the flap 30. The front wall portion 28 of the flap 24 also carries near its bottom edge and substantially at its mid-width location a third snap fastener element 42 and the bottom flap 33 carries in its front wall portion 36 a complementary snap fastener element 43 with which the element 42 is engageable to releasably connect the flap 24 to the flap 33.

The flaps 24, 30 and 33 are preferably formed of leather of a thickness somewhat less than the thickness of the back plate 21 and when the flaps 24, 30 and 33 are secured together by the separable fasteners, as illustrated in the drawing, they constitute a receptacle which closely fits a lamp battery to be carried in the battery case. This receptacle can be quickly opened to replace a battery therein and can be quickly closed after a battery has been placed in position therein.

The strap 20 loosely supports the battery case from the belt strap 12 so that the battery case is not bound tightly to the body of the wearer and the looseness of the battery case relative to the belt can be varied by adjusting the strap 20 in the buckles 18 and 19. The position of the battery case relative to the hip of the wearer can also be varied by properly adjusting the strap 20. This loose connection between the battery case and the belt strap prevents the battery case from chafing the skin of the wearer or causing other discomfort and the large back plate 21 of heavy moisture and acid-resistant material protects the battery against the perspiration of the wearer and also protects the clothing of the wearer against battery acid if the battery should leak.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A battery case comprising a normally vertical back plate adapted to be secured to a support, a receptacle comprising a bottom wall on and projecting forwardly from the lower part of a side of the back plate, a front wall on and rising from the forward edge of said bottom wall and forwardly spaced from said back plate, and side walls on the side edges of said front wall projecting rearwardly thereon to the region of said back plate, a closure flap comprising a first vertical side wall portion secured to said plate along a side edge thereof, said first side wall portion projecting forwardly from said back plate along the outer side of the related side of said receptacle, said closure flap further comprising a front plate on and projecting laterally from a forward part of said first side wall portion and extending across the forward side of said receptacle toward the side of said back plate remote from said first side wall portion, and a second vertical side wall portion on said front plate projecting rearwardly toward said back plate and having a free vertical edge unconnected to said back plate, said second vertical side wall portion normally extending along the outer side of the side of the receptacle remote from said first vertical side wall portion, and fastening means acting between said second vertical side wall portion of the closure flap and the adjacent side wall of the receptacle releasably holding said

closure flap in closed position to retain a battery seated in said receptacle.

2. A battery case comprising a normally vertical back plate adapted to be secured to a support, a receptacle comprising a bottom wall on and projecting forwardly from the lower part of a side of the back plate, a front wall on and rising from the forward edge of said bottom wall and forwardly spaced from said back plate, and side walls on the side edges of said front wall projecting rearwardly thereon to the region of said back plate, a closure flap comprising a first vertical side wall portion secured to said plate along a side edge thereof, said first side wall portion projecting forwardly from said back plate along the outer side of the related side of said receptacle, said closure flap further comprising a front plate on and projecting laterally from a forward part of said first side wall portion and extending across the forward side of said receptacle toward the side of said back plate remote from said first side wall portion, and a second vertical side wall portion on said front plate projecting rearwardly toward said back plate and having a free vertical edge unconnected to said back plate, said second vertical side wall portion normally extending along the outer side of the side of the receptacle

remote from said first vertical side wall portion, and fastening means acting between said second vertical side wall portion of the closure flap and the adjacent side wall of the receptacle releasably holding said closure flap in closed position to retain a battery seated in said receptacle, and additional fastening means acting between said front plate of the closure flap and the front wall of said receptacle for further releasably holding the closure flap in closed position.
